(57) **CLAIM**

The ornamental design for a combination dry erase board and easel pad surface, as shown and described.

DESCRIPTION

FIG. 1 is a perspective view showing the new design for a combination dry erase board and easel pad surface; FIG. 2 is a left side view thereof, the right side view being a mirror image thereof;

FIG. 3 is a front view thereof;

FIG. 4 is a rear view thereof;

FIG. 5 is a top view thereof; and,

FIG. 6 is a bottom view thereof.

The features of the design as claimed by applicants are shown in bold lines. The features shown in dotted lines are not claimed and are provided for illustrative purposes only.
